UNITED STATES PATENT OFFICE.

GEORGE RACTLiffe, OF NEW YORK, N. Y., ASSIGNOR, BY MESNE ASSIGNMENTS, TO
JOHN T. PRATT, OF NEW YORK, N. Y.

INTERNAL-COMBUSTION ENGINE.

1,108,473.

Specification of Letters Patent. Patented Aug. 25, 1914.

Application filed January 6, 1913. Serial No. 746,393.

To all whom it may concern:

Be it known that I, GEORGE RACTLiffe, a subject of the King of Great Britain, and a resident of the borough of Bronx, city, 5 county, and State of New York, have invented certain new and useful Improvements in Internal-Combustion Engines, of which the following is a specification, reference being had to the drawings hereto attached and made a part hereof.

My invention relates to engines, and more particularly that class known as "internal combustion engines", or in which the conditions regarding valve control of the gases 15 to and from the cylinder are such as to require special construction, and my improvements pertain to valves, valve arrangement and operation and features pertinent thereto.

As a result of my invention more effective valve control, a lightening of the moving parts, advantages of replacement and repair, economy of construction and other features of superiority or benefit in the 20 manufacture or operation will be apparent.

While the features of my invention are more specifically set forth in the claims, I have shown a particular form of embodiment of my invention in the drawings here- 25 attached, in which—

Figure 1 is a vertical section through an engine cylinder. Fig. 2 is a transverse section through the top of the cylinder on line 2—2, Fig. 1. Fig. 3 is a side view of a 35 valve and stem. Fig. 4 is a top plan view of the valve as shown in Fig. 3.

In the drawings, A is a cylinder; B a crank-case; C a cylinder-head; D cylinder-head cover; C' is the cylinder-head extension; E is a ring sometimes called "junk ring"; F, F' are inlet and exhaust valves; 40 G, G' are valve stems; H, H links; J are bell crank levers; K, K are eccentric links; L, L are crank pins on valve shafts M, M. 45 On the valve stem G is a shoulder on which rests a collar f, through which projects a shank f' having a nut f''. The inlet and outlet ports are N, N leading to recessed portions P, P of the inner wall of the cylinder. 50

In the embodiment of my invention shown, it will appear that the engine cylinder A has the usual piston to reciprocate in it with connecting rod to crank pin, to 55 operate a crank-shaft in the crank-case B.

In the cylinder A the upper end is so cast that recesses P, P may be counter-bored from the top on the arc of a circle a short distance from the upper end of the cylinder. This counter-bore extends to the inlet and outlet and connects with the ports N, N so that the inlet or outlet of gases through the inlet or outlet ports will pass through the counter-bore portion P, P, except when the opening from the port to the counter-bore is closed by the valves F or F'. Longitudinally through the wall of the cylinder a hole is bored to accommodate the valve stem G. At the top of the valve stem G is a shoulder on which rests a collar f through which passes a shank f' on which the valve F fits, and as shown is secured to a nut f'' secured to the end of the shank.

The lower end of the valve stem G is connected by link H to a bell crank lever J, which is operated by eccentric link K, in turn moved by the crank or eccentric pin L, which is a pin mounted eccentrically on a valve-shaft M, which may be made in any suitable form. Any usual gear or chain 75 connection (not shown) from the crank-shaft may be used to properly operate the valve-shafts at proper speed ratio and timing.

On the upper end of the cylinder A, the cylinder-head C is bolted and has the extension C' projecting into the upper end of the cylinder a sufficient distance to engage the inner surface of the valves F, F', except that between the head C and the valves there is a packing or junk ring E, which may be of suitable form to effect the purposes of a packing ring. The projection C' of the head C is cut away on opposite sides, or at points opposite the ports N—N, but only to such extent that the junk ring still amply engages and supports the valves F—F' and also permits the inlet and outlet of gases. That is the extension C' projects from the upper end downwardly into the cylinder, an extent which will not interfere with the piston, but sufficient to support the valves F and F', and at which a recess or scallop is cut in the projection, so as to leave support for the valve, but afford sufficient opening for gases to pass out or in.

In the construction and operation of the engine it will be seen that the valve F is made in a form simple and cheap to manufacture, the recesses or counter-bores P, P

are simple and cheap to make in the cylinder, and are very simple to provide for in the casting of the cylinders. I make the valve F or F' short longitudinally so that it is just sufficient to properly cover the inlet or exhaust port for which it is intended, with the necessary overlap, and by so doing reduce the weight of the valve proper to a minimum, thereby minimizing the weight of reciprocating parts and the minimum of wear and friction involved in the reciprocating of the valve. By reducing the size of this valve to a minimum, the cost is reduced and the expense of replacement in case of wear is minimized. The stem G while attached, as above described, to the valve, may be secured in any suitable way, the collar f being a removable collar engaging the small shoulder on the stem, to increase the surface of engagement between the stem and the valve which may be further increased by modification in dimensions and arrangement. By having this removable collar f, the valve stem G may be inserted from the lower end of the cylinder A and the valve put in place from above, and may be replaced from above without removal of the stem. The connection at the lower end of the stem with the link H may also be modified so that the stem proper may be uncoupled and removed with the valve attached, mechanically fixed or integrally at the upper end, as desired, to meet certain conditions of operation, by welding the valve head to the stem, although in my preferred form I construct the valve and stem as shown. By minimizing the longitudinal height of the valve F, the bearing surface in the same requiring lubrication is minimized, and the surfaces between the valve and the recesses or counter-bores P, P', and between it and the junk ring E, becomes a more simple and easy matter. The holes longitudinally through the cylinder-walls to accommodate the valve stem G, are such in size and position that the question of leakage becomes negligible, and the clearance can be made such as to insure perfect lubrication and accommodation for any variation in expansion owing to the heating and cooling of the cylinders.

It will be noted that the cylinder-head cap D covers the cylinder-head, forming a water-jacket which may be connected with the cylinder water-jacket so as to complete a water-jacket over the cylinder and head coming in close contact with the walls adjacent to the valve recesses, and therefore insuring the reliability of lubrication between the recesses and the valves and preventing over-heating of the valves and their connections. The arrangement of the cylinder-head with the spark plug in the center, as shown, affords the advantage of central ignition and the possibilities of a symmetrical

explosion chamber, the desirability of which does not here require discussion.

It will be apparent that various modifications in detail are within the scope of my invention other than the particular form which I have shown and herein described, without limiting myself thereto, but

What I claim and desire to secure by Letters Patent is:

1. In an internal combustion engine, a cylinder, a plurality of ports near the head of said cylinder, valve mechanism for each port comprising a recess in the inner wall of the cylinder open on one side to the combustion chamber, and extending from the upper end of the cylinder to a point slightly beyond the port, a projection on the inside of the cylinder head concentric with the inner surface of the cylinder wall proper, a valve for each recess having its outer side symmetrical with the outer wall of its recess, and its inner side substantially flush with the remaining surface of the inner wall of the cylinder, a valve stem for each of said valves to operate them independently one of the other, said valve stems passing through holes in the cylinder wall parallel with the axis of the cylinder and adapted to reciprocate said valves respectively, valve mechanism in the crank-case of the engine operated by the engine to reciprocate said stems. 80 85 90 95

2. In an engine, a cylinder and cylinder wall having inlet and outlet ports, a cylinder-head to close one end of said cylinder, a circular projection on said head extending inwardly below the top of said cylinder wall, recesses in the cylinder wall counter-bored from the inside of and extending from the head end of said cylinder and forming spaces adjacent to said ports partly inclosed by the inner extension of said cylinder-head, valves fitting said spaces with inner faces flush with the interior cylinder wall and of a width slightly in excess of the width of said port openings, a stem for each of said valves extending from said valve space to the lower end of said cylinder and connections to operate said valve stem. 100 105 110 115

3. In an internal combustion engine, inlet and outlet ports near the head of the cylinder, a main cylinder section, a water-jacket therefor, a cylinder head, a piston having a predetermined movement in said cylinder, two separately disposed counter-bores about the top of said cylinder above the limit of movement of said piston, valves in said counter-bores adapted to engage the outer surface thereof and having their inner surfaces concentric with the upwardly projected surface of the cylinder wall above the limit of movement of said piston, a stem for each of said valves projecting through the cylinder proper and valve operating mechanism to move said stems and valves. 120 125 130 135

4. In an internal combustion engine, a cylinder having a main portion with water-jacket, a cylinder head, the main portion of said cylinder having its inner surface cylindrical throughout its length to within a short distance of the upper end, the upper end of said inner surface being expanded to form two separate recesses connecting with the inlet and outlet ports of the cylinder, valves conforming to the shape of said recesses and engaging on their inner surface and inner projection of the cylinder-head, a cylinder-head having a cylindrical inner projection and a lateral flange for attachment to the head of the cylinder, operating mechanism between said valves and the moving parts of said engine for the purpose described.

5. In an internal combustion engine, a valve mechanism comprising a recess cut into the inner wall of the cylinder for only a part of the length of the cylinder, a port in the outer wall of the cylinder connecting with said recess, a valve in said recess conforming on its outer side to the wall of the recess and on its inner side conforming to the extension of the inner surface of the cylinder, means extending from the top of the cylinder above the piston throw to the crank chamber and located outside the inner surface of the wall of the cylinder to operate said valve.

6. In an engine, a cylinder head, an annular projection on said cylinder head extending into the end of said cylinder, a recess cut from the inner wall of said cylinder and opposite said projection adapted to receive a slide valve between it and the projection, a port contiguous to said recess, a recess cut in the inner edge of the projection from the cylinder head, said recess registering with the recess in the cylinder wall to form a passage-way from the interior of the cylinder to the port, a valve in said re-

cess and means for slidably reciprocating the same.

7. In an internal combustion engine, a valve mechanism comprising a recess in the inner wall of the cylinder adjacent to the top thereof adapted to receive a valve, a valve in said recess, a head for such cylinder having a projection into the end of the cylinder with an outer cylindrical surface fitting the inner cylindrical surface of the cylinder proper to form the lateral support for the valve in the recess, valve operating means in the crank chamber of the engine, and connections between the valve and the operating mechanism located outside of the inner surface of the cylinder wall, whereby the operating connections are not in contact with the piston.

8. In an internal combustion engine, a valve mechanism comprising a plurality of recesses in the inner wall of the cylinder adjacent to the top thereof, each adapted to receive a valve, a valve in each of said recesses having its inner side flush with the inner wall of the cylinder and extending outwardly in the recess, whereby the center of each valve is located outwardly beyond the normal surface of the cylinder wall and registering with the axis of the valve stem lying parallel to the axis of the cylinder but outside of the inner wall of the cylinder, a valve stem for each of said valves engaging the center of said valves and means for reciprocating said stems to operate the respective valves independently of each other.

In testimony whereof, I have signed my name to this specification, in the presence of two subscribing witnesses, this 3rd day of January, 1913.

GEORGE RACTLIFFE.
